UNITED STATES PATENT OFFICE

ALEXANDER SOLDENHOFF, OF ZURICH, SWITZERLAND

FLYING MACHINE

Application filed May 19, 1931, Serial No. 538,550, and in Germany May 22, 1930.

My invention relates to a flying machine comprising a single wing body only, generally speaking, which consists of a median part of comparatively thick cross-section, 5 which I term hereinafter the "main body", and two lateral members integral therewith and shaped to form each a plurality of wing members of reduced cross-section, so that the machine resembles a single deck aeroplane, 10 as regards in the main body, and a multiple plane flying machine, as regards the two end members thereof, while the surface area of the supporting parts increases at a higher rate than the span across the wing members. 15

In a flying machine of this type it is of advantage to mount the driving means such as motors and propellers, entirely within the interior of the main body and I therefore 20 so construct the latter that the currents of air produced by the driving apparatus, will be allowed to pass through the said main body, either by providing suitable apertures in the front and rear walls thereof or by 25 dividing the main body into two surfaces or planes and providing, if preferred or required, in the open space reinforcing struts or profiled partitions for subdivision in vertical direction. In order to interconnect the 30 two lateral parts of the main body for communication I provide a gangway in the lower part or in the upper part of the main body, or if the flying machine is equipped with a boat, I utilize the same for the interconnecting 35 purpose, the chief object of a wing construction of this cargo-room type rather residing, a part from that, in the possibility of transferring all loads away from the longitudinal axis and towards the outside, that 40 is, to the width or span across the wings, and approximately to a point where the thick main body divides into the outer wing members of reduced cross-section.

The idea of enlarging the usual or normal 45 wing surfaces simply in geometrical regards so that the profile in the median line will have a sufficient constructional height for accommodating therein all not-supporting parts and loads, is universally known. The increased dimensions of the wing, in case of a

single deck, aeroplane, will thus result in an unexpected wide span and as the absolute weight of the structure necessarily, must rapidly increase, corresponding to the increase of the span, in order to comply with 55 the increased stresses, while the loading capacity does not increase in conformity thereto and even will be reduced by the excess of the adequately increasing constructional or total weight, the enlargement of the machine 60 which in itself is very desirable, yet will be highly uneconomical and will be barred practically to limits which cannot be surpassed except by adopting any other system of construction. 65

A further disadvantage of a normal wing enlarged only in geometrical respects, resides in the fact that in the endeavour to transfer the loads from the centre away towards the sides whereby the above disadvantage 70 respecting the increase of the constructional or total weight might partly be overcome to a certain degree, the aerodynamic properties of the wing will be impaired, particularly the cross-stability and consequently the reliability of flight. For if the action of the air power is unsymmetrical or preponderates unilaterally as frequently happens at the extremity of a wing, the cargo or loads will occupy, just as on an inclined plane, an adverse or obnoxious position with relation to the steering control, since in such a case the lateral balancing rudder concerned will not be able to lift the injured wing but rather act to check the course thereof and to impair 85 the flight.

It has also been suggested heretofore to enlarge aeroplanes to form the nothing-but-wing type by widening out the body or hull towards and to the supporting plane so as 90 to shape the same to form a thick wing, and substituting, for the tapering extremities of a large span, thinner wings firmly attached to the stepwise reduced main wing. In this way the central part will be available for the 95 accommodation of cargo and loads, but a corresponding gain of surface area will not be attained thereby. For reasons of reliability of flight aeroplanes of such a construction necessarily must have or retain the aerody- 100

namically indispensable tail member with the rear rudder, and in many cases aeroplanes of this sort are provided with two or more tail members so that they cannot be compared with a nothing-but-wing machine having a wing-control, herein referred to.

In contrast with the aeroplanes above mentioned, the so-called arrow-like shape or the wing of arrow shape is in a most favourable condition, because in case of distributing the load in or within the span across the wings, the same instead of being moved laterally only, will be transferred at the same line backwards due to the changed position and direction of the wings, and, therefore, unilaterally acting air forces will be caused to act in inclined or diagonal direction towards the front and thus be balanced by means of the horizontal steering control, in the direction of the longitudinal axis of the aeroplane. For this reason the higher cross stability of an aeroplane of the arrow-type will be particularly suited for such enlargements and transference of load.

If aeroplanes of the said arrow-type, however, are enlarged in geometrical respects only, they cannot descend to earth on smaller landing places and also require large rooms for accommodation on account of the wide span across the wings. Further as regards the torsional forces inherent to a higher degree in aeroplanes of the arrow-type, there will be the same disadvantage, because the required constructional rigidity and firmness involves a correspondingly greater constructional or total weight, so that in spite of the transfer of the loads towards the outside and the possibility of relating stresses to local constructional members only, resulting therefrom, the total weight likewise increasing in accordance with the increased span and torsional forces, will balance or annul the above advantage, that is to say, the relation between the tare or weight when empty and the useful capacity still will be disadvantageous in economical respects.

From the above observations I am led to suggest a new construction of an aeroplane of the arrow type whereof the increase of the size of the supporting surfaces does not depend upon a like increase of the span across the wings. In the new construction constituting so to say, a single wing or a nothing-but-wing structure, the latter comprises a main or median body of great thickness or high profile wherein all loads and nonsupporting parts of the aeroplane are accommodated, and an outer part consisting of two or more thin wings firmly attached to the thick main body, so that the surface will be capable of enlargement with relation to the span by any desirable multiple, and at the same time the centre of gravity or the means of the aerodynamic pressure of the air forces, that is the resultant, can be calculated by

means of the contour of the surface of the selected camber and the attaching angle of the thin surfaces, for any desired position in vertical direction in the longitudinal axis of the aeroplane. Moreover, as the said thin wings must be reinforced as usually by stay-ing or stiffening means, a considerable econ-omy of total weight will result therefrom. The advantages concomitant with a wing of the described construction are apparent. The height of the profile may be increased to any desired degree, since the median wing or main body can be made to increase towards the outside, because the outer wings share the height and the lateral wall of the median body remaining therebetween will act, so to say, as end members of the thin profiles or wings, and may be equipped with a door and windows. The said thin wings may be of greatest thickness at the root and taper from the thick main body to the extremities thereof or they may be of equal thickness throughout, just as desired or preferred.

The essential feature of my improved flying machine resides in the lateral elongation of the main body to form projecting thin wings superposed in the manner of a multiple plane flying machine, and which may be geometrically similar to the said main body or of any other desired constructional shape and contour so as to contrast with the profile median line, the symmetry line, the camber and the like of the main wing or body, the attaching profiles of the thin wings also may terminate with their front and rear edges within the contour of the end profile surface of the main body, or they may jut out, as regards depth, in the front and in the rear, so as to partially project freely, thus for example the lowermost wing may project beyond the main body in the front thereof and coincide therewith towards the middle thereof, while the same may likewise increase in depth considerably towards the rear and terminate to form a boat in the longitudinal axis.

In the accompanying drawings forming a part of this specification, Figures 1, 6 and 11 are views in top plan of a flying machine of the nothing-but-wing type constructed in accordance with the present invention and whereof the longitudinal axis or centre line, as a primal or original profile of the median wing or main body *b*, *a*, *b*, is denoted by *a*, the lateral ends or end profiles of the same being indicated by *b*, while *c*, *d* and *e* are the outer or thin wings. It will be seen that the two wings *c* and *d* are of the same contour and superposed to coincide in Figure 1, whereas in Figures 6 and 11 they are of different shapes and sizes and superposed in staggered relationship. In all figures *c* denotes the uppermost lateral or thin wing, *d* indicates the next following or lower wing while *e* denotes a third or lowermost wing (if any provided)

(see claim 10) of the set. Figures 2, 3, 7 and 12 are views in elevation or front views of the aeroplane, and Figures 4, 5, 8, 9, 10 and 13 are side views of the same, the front edge or nose of the respective wing being indicated by *n* and the rear edge by *k*.

Figures 6 and 7 show the apertures *W* in the direction of flight which are also shown and indicated by *M* in Figure 12, for the accommodation of propellers. The embodiments illustrated in Figures 2 and 3 are distinguished from each other by that, in Figure 2, part of the profile surface *b*—side wall extending in the direction of flight—between the outer wings *c* and *d* remains free, in the sense of claims 2 and 3, as also in the embodiments shown in Figures 4, 5, 7, 9 and 10, whereas in Figure 3 the thick median wing or main body is elongated to form the said outer wings without the provision of any vertical end or side walls intermediate between the roots of the said outer wings, Figure 12 showing these various feasibilities or modifications in connection with the same formation of the median wing or main body as illustrated in Figure 5 in side view.

In Figure 9 the profile *a* is flat and plain at the bottom and has a concave profile at *b*, while the outer wings *a* flat or plain upper wing and a concave lower wing, the top surface and the bottom surface, respectively, of the lower wing being flush with the corresponding surfaces of the main body, see claim 6.

In Figure 10 the upper surfaces and the lower surfaces of the outer wings are of similar construction and shape (see claim 6) but in connection with a main body *b* of modified construction including a concave main profile and a convex root profile *a* (see claim 2). In this modification the main body is clearly wound or twisted and the upper outer wing *e*, as regards its symmetry line or convexity, highly contrasts with the end profile *b* of the main body. Figures 9 and 10 illustrate the modification claimed in claims 4, 6, 7 and 8. Figure 8 shows a combination of similar profiles, whereof all surfaces on the inside and outside are of the same medium convexity or curvature (see claim 7) so as to possess flat bottom surfaces and convex symmetry lines. In the embodiment shown in Figure 8 a third surface is provided and denoted by *e* which, corresponding to that depicted in Figure 6, projects beyond the profile *b* (see claim 10), Fig. 7 showing a front view thereof. The character *g* indicates the flat boat surface constituting the rear continuation of the wing surface *e* (shown in hatched lines) which terminates in the longitudinal axis *a* as a keel-boat, *g*, *a*.

In Figures 1 and 11 the points indicated by *L* are worth mentioning since they are the places to which the loads removed from the axis or centre *a* are to be transferred.

The arrow *L*—*L* in said figures indicates the direction of transfer or, inversely, the direction of the air force transmission in case that a unilateral stress occurs at the end of a wing. Such indicates the gravity centre line over the resultant in the centre of the aeroplane. The two dotted lines *h* extending from the profile *a* over *b* towards and to the outer wings indicate the longérons of the main body and the outer wings, and Figure 1, therefore, shows, how the transferred loads are supported by the longeron plane. In this embodiment the elements of construction are subjected to stresses locally and a construction of this kind involves a marked economy of the constructional or total weight of the structure due to the advantageous distribution of the loads within the span across the wings.

Figure 14 is a perspective view of the embodiment illustrated in Figure 11, the arrow below the Figure 14 indicating the direction of flight, while the door and windows are shown in cross-section, just as in Figure 13, reinforcing struts and staying means between the outer wings being omitted for clearness sake.

Obviously my improved nothing-but-wing construction is applicable for structures or flying machines of a small type, wherein the pilot's post of duty is provided in the main body in lieu of a seat in the usual hull of aeroplanes as hitherto constructed, the usual carriage being adapted to be drawn in and accommodated within the main body after starting, so that the aeroplane will constitute a nothing-but-wing machine during the flight.

The particular advantages and advance in the art secured by my improved machine, reside in the fact that the total weight is comparatively low, a comparatively large cargo can be accommodated therein and the specific load on the surfaces is reduced to a minimum due to the enlargement or increase of the surface areas exceeding beyond the concomitant increase of the span across the wings, so that both the reliability and the economy of the machine will be greatly improved.

What I claim is:

1. Flying machine of the character set forth including a plurality of supporting surfaces and constituting, in general, a structure of arrow shape comprising a thick main body or wing and a plurality of thin outer wings superposed and spaced to form sets on either side of the said main body or wing, of an appearance similar to that of a multiple plane flying machine.

2. Flying machine of the character set forth and claimed in claim 1, wherein the thick main body is divided, over part of its cross-span, into two superposed and spaced surfaces.

3. Flying machine as claimed in claim 1,

wherein the thick main body is provided with or shaped to form one aperture or several spaced apertures, passages or gangways extending from the front end towards and to the rear end and adapted for the accommodation of the driving apparatus.

4. Flying machine as claimed in claim 1, wherein the main body constitutes, over the full of its cross-span or width, a closed single deck structure, whereof the thickness or height of profile increases towards the outer ends.

5. Flying machine as claimed in claim 1 wherein the main body has differently convex or curved profiles, so that the primal or root profile thereof possesses, in the longitudinal axis of the machine, a central curvature or symmetry-line different from or contrasting with the end profiles thereof, and thus has a flat, concave or convex bottom side while the bottom sides at the outside are to the contrary, so that the said median body in itself is twisted, while the outer wings projecting therefrom have not the same profile at the root thereof.

6. Flying machine as claimed in claim 1, wherein the thick median body has attaching surfaces for the outer wings of any desired form and span, the said surfaces being disposed to converge towards the rear to the longitudinal axis of the machine.

7. Flying machine as claimed in claim 1, wherein the outer wings even if they differ from each other respecting shape, attachment and curvature, are shaped to form a continuation of the upper surface curvature and the lower surface curvature of the main body, the top side of the uppermost outer wing corresponding to or lying flush with the top side of the main body and the bottom side of the lowermost outer wing corresponding to or being flush with the bottom side of the main body.

8. Flying machine as claimed in claim 1, wherein the outer wings are shaped, at the root thereof, to form or have a profile geometrically similar to the end profile of the main body, independently of whether or not other parts of the latter or the outer wings are of varied form.

9. Flying machine as claimed in claim 1, wherein the thin outer wings are shaped, at the point of attachment to the thick main body, to form or have a profile different from or contrasting with that of the said main body, no matter whether the profiles of the outer wings are alike or different from each other.

10. Flying machine as claimed in claim 1, wherein all wings, both the thick main body and the thin outer wings are of the same constant profile.

11. Flying machine as claimed in claim 1, wherein the lowermost of the outer wings projects, in the front, with its nose edge be-

yond the attachment towards the interior and rejoins towards the longitudinal axis so as to form a boat or float.

In testimony whereof I affix my signature.
